Primary Examiner — Michael A Maharajh(74) *Attorney, Agent, or Firm* — Sterne, Kessler, Goldstein & Fox P.L.L.C.(57) **CLAIM**

The ornamental design for a therapeutic device, as shown and described.

DESCRIPTION

FIG. 1 is a top front isometric view of a therapeutic device showing the claimed design;

FIG. 2 is a bottom rear isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the figures show portions of the therapeutic device that form no part of the claimed design.

1 Claim, 4 Drawing Sheets(56)
